Harry Hook,

UNITED STATES PATENT OFFICE.

HARRY HOOK, OF PHILADELPHIA, PENNSYLVANIA, ASSIGNOR TO PARTRIDGE
& RICHARDSON, OF SAME PLACE.

DESIGN FOR GIMP.

SPECIFICATION forming part of Design No. 22,245, dated February 28, 1893.

Application filed January 25, 1893. Serial No. 459,739. Term of patent 3½ years.

To all whom it may concern:

Be it known that I, HARRY HOOK, a citizen of the United States, residing in the city and county of Philadelphia and State of Pennsylvania, have invented a certain new and original Design for Gimp for Dress Trimmings, of which the following is a full, clear, and exact description.

My design as illustrated in the accompanying drawing, comprises a series of flat open-centered coils, *a*, of cord, arranged with the individual coils at selected distances apart, along a band *b* of breadth inferior to the diameter of the coils. The band *b* is similarly composed of a cord, disposed in a path which may be described as sinuous or consisting of repeated uniform transverse folds. From an inspection of the drawing it will be observed that both the coils and the band are formed from a single continuous cord, which, after being laid in transverse folds to form a section of the band of a required length, and being secured by a binding thread, is thereupon laid in spiral arrangement to form a flat coil having an open center, the portions of the layers of cord of the coil in the region of one side

of its body existing in the same plane as the adjoining section of the band, to constitute in effect a continuation of said band, while the remaining portions of the layers of the coil pass freely above, across the face of, and below, the body of the band. The cord of the outer layer of the coil is, at the proper point, turned away from the coil, and folded upon itself in the manner described to form a succeeding section of the band. 35

As will be observed from the illustration, the ornamental gimp herein described has the appearance of consisting of a series of coils strung upon a continuous independent band which passes through their centers. 40

Having thus described my invention, I claim—

The design for gimp for dress trimmings herein described and illustrated. 45

In testimony that I claim the foregoing as my invention I have hereunto signed my name this 20th day of January, A. D. 1893.

HARRY HOOK.

In presence of—

F. NORMAN DIXON,
MONTGOMERY RUSSELL.
